his Attorney

UNITED STATES PATENT OFFICE.

WILLIAM E. WINE, OF TOLEDO, OHIO.

DOOR MECHANISM FOR RAILWAY CARS.

Application filed December 21, 1923. Serial No. 681,995.

To all whom it may concern:

Be it known that I, WILLIAM E. WINE, a citizen of the United States, residing at Toledo, in the county of Lucas and State of Ohio, have invented certain new and useful Improvements in Door Mechanism for Railway Cars; and I do hereby declare the following to be a full, clear, and exact description of the invention, such as will enable others skilled in the art to which it appertains to make and use the same.

This invention relates to a door mechanism for railway cars or the like, and has for its principal object to provide an improved construction whereby hinged car doors may be closed and held in such position. Another object of the invention is to provide an improved arrangement of door supporting members by which accidental disengagement of the parts is prevented. With these and other objects in view the invention consists in the construction, combination and arrangement of parts hereinafter described and claimed.

25 In the accompanying drawings which show a preferred form of the invention,—

Figure 1 is a fragmentary side elevational view of a portion of a car embodying door mechanism involving the invention.

30 Figure 2 is a detail end elevation of the construction shown in Fig. 1.

Figure 3 is a sectional view on the line 3—3, Fig. 1, a removable prying lever for forcing the door to closed position being indicated in dotted lines.

Figure 4 is a diagrammatic view showing the general arrangement of the doors.

Figure 5 is a view diagrammatically illustrating the relation of the door mechanism to a car of the twin hopper type.

The car chosen for illustrating the invention is of the twin hopper type wherein, as shown for example in Wine Patent No. 1,431,506, dated Oct. 10, 1922, two doors arranged transversely of the car are spaced apart slightly and held in such spaced relationship by means of a door spreader which forms a stiffening beam for supporting the doors. The car includes a hopper end sheet 1 which is disposed in an inclined plane so that the width of the car at the hopper is less at a point near the rail than at a point further up from the rail. Attached to the hopper end sheet is a sloping floor sheet 2, the hopper discharge opening being defined in part by the edges of the end sheet and

the floor sheet 2. Two of these hoppers are provided at each end of the car and they are arranged on opposite sides of the center sill. A door 3 is provided for each hopper discharge opening, said doors being hinged to the car body at points near the uppermost edges of the discharge openings. This construction is well known in the art.

The edge of the hopper end sheet 1 defining the discharge opening is outwardly offset at 4 to form a shoulder 5 against which the door 3 may seat when closed. The door is similarly provided with an outstanding marginal flange 6 which borders the outer edge of the door and forms with the outermost edge 7 of the offset portion of the side sheet 1 a pair of parallel sealing flanges preventing escape of lading from the hopper. A stiffening angle iron 8 may be secured along the lowest edge of the sloping floor sheet 2 in the customary manner.

The door spreader 9 is shown as formed of a steel plate having a flange 10 lying against the outer face of the door and secured thereto by means of rivets 11. The web 12 of the door spreader projects outwardly or is outstanding from the plane of the door and its outermost edge is defined by an upstanding marginal flange 13. The door spreader is preferably located near the free edge of the door and extends directly across the car horizontally from a point slightly outside of one hopper end sheet 1 to a point slightly outside of the corresponding hopper sheet on the opposite side of the car. The door spreader is thus of slightly greater length than the adjacent width of the car and its general line of direction is parallel to the free edges of the doors.

The door may be held in closed position by means of the door supporting hooks 14, one of which is pivotally attached to each hopper end sheet 1. These hooks are preferably provided with preliminary supporting ledges, such as 15, and with final supporting ledges 16, which by engaging the door supporting arms constituted by the projecting ends of the door spreader enable the door to be maintained either in partly closed position or in fully closed position. Each hook 14 is spaced away from the general plane of the adjacent hopper end sheet 1 a sufficient distance to permit it to swing freely along the outer face 7 of the offset portion of the side sheet. Pivot brackets for the hooks are mounted

upon the hopper end sheets just behind the offsets 4 thereof. Each of these brackets may advantageously embody two portions, namely, the base portion 17 lying directly against the outer face of the hopper end sheet and an outer plate portion 18 spaced slightly from the base portion, the pivot end of the hook being operatively disposed between these two portions. An eccentric locking pawl 19 may also be pivotally mounted between these two portions for the purpose of holding the hook 14 in engaged relation with the door arm when the door is closed. The bracket members 17 and 18 are connected by the rivets securing them to the car. The inner portion 17 of the bracket is of less extent than the outer portion 18 thereof and terminates when mounted on the car a short distance behind the offset portion 4 of the hopper end sheet. The outer plate portion 18 of the bracket is of greater size and is arranged to extend outwardly over the offset portion 4 to a point near the outermost edge of the side of the hopper end sheet 1. A space or way is thereby formed between the inner face of the portion 18 of the bracket and the outer face of the portion 7 of the adjacent hopper end sheet. The hook 14 operates freely in this space or way and at the same time is held in alignment transversely of its pivot. By this arrangement the hook is guided near its point of engagement with the door spreader 9, the bracket serving to support the hook in one direction and the edge 7 of the hopper end sheet supporting it from the opposite side. The hook 14 swings in an inclined plane preferably agreeing with the incline of the hopper end sheet. It engages beneath a locking face or extension 20 of the door contacting flange 10 of the door spreader to hold the door closed. A flange 21, which is formed along the outermost edge of the spreader, lies substantially normal to the plane of the locking face 20 so that should any weaving of the car occur tending to slip the end of the spreader off the hook such slippage will be arrested by contact of this end flange 21 against the side of the hook.

At 22 is indicated a clearance line such as defines the equipment limits of many railroads. In order that no part of the present device may extend beyond this line when the car settles and the springs go solid or when the car is operated on a curved track, the outer ends of the door spreader 9 preferably terminate on lines approximately parallel with the respective planes of the adjacent door hooks 14. The lowermost corner of this spreader may go back still further along the inclined line to keep it well within the clearance limits.

An aperture 23 is provided in the outer end of the hook so that a removable door

prying lever 24 may be entered there-through and brought into engagement with the door for forcing the latter from a partly closed to a fully closed position.

While I have described a preferred embodiment of my invention, other embodiments thereof are contemplated within the scope of the appended claims.

I claim:

1. A railway car having a hopper with a discharge opening therein, a hinged door for closing said discharge opening, said car involving a side sheet having an edge defining a portion of said opening, said edge being outwardly offset from the main portion of said side sheet to form a seat for the adjacent edge of the door, said door having an arm extending outwardly beyond said offset, a bracket member carried upon said side sheet behind the offset therein, a door supporting member pivoted upon said bracket member so as to swing in a plane parallel with the said side sheet and over the said offset portion thereof and adapted to have supporting engagement with said door arm, and means connected to said bracket member and arranged to overlie and guide the said door supporting member, said means being spaced outwardly from and overlapping the offset portion of said side sheet and forming therewith a way for the said supporting member.

2. In a railway car, the combination with a car side sheet having an offset along one of its edges, of a hinged door having an edge adapted to stand adjacent said offset, a door supporting member, and a bracket mounted on said side sheet behind the said offset and embodying a pivot for said door supporting member and including an inner portion arranged for contact with the main portion of said side sheet and an outer portion connected to said inner portion and overlying said door supporting member, said inner portion terminating behind the offset in the said side sheet, and said outer portion extending beyond and overlying the said offset.

3. A railway car of the twin hopper type having a door hinged along its upper edge with its free lower edge extending transversely of the car, an arm secured to the door near the free edge thereof and extending outwardly beyond the edge of the door and beyond the car side, and a door supporting member pivoted upon the side of the car and adapted to supportingly engage the said arm, the outer end of the said arm being formed at an outwardly and upwardly inclined oblique angle with the free edge of the door.

4. A railway car of the twin hopper type having a door hinged along its upper edge with its free lower edge extending transversely of the car, an arm secured to the

door near the free edge thereof and extending outwardly beyond the edge of the door and beyond the car side, and a door supporting member pivoted upon the side of the car and adapted to supportingly engage said arm, the portion of the car side carrying the said door supporting member lying in a plane at an acute angle with the vertical and the said door supporting member 10 lying in a plane parallel thereto, and the end of the door arm being disposed in a plane substantially parallel with the plane of the door supporting member.

5. A railway car of the twin hopper type having a hinged door with its free edge extending transversely of the car near the rail, an arm secured to the door near the free edge thereof and extending outwardly beyond the edge of the door and beyond the car side, and a door supporting member pivoted upon the side of the car and adapted to supportingly engage the said arm, the portion of the car side carrying the said door supporting member lying in a plane at 20 an acute angle with the vertical and the said door supporting member lying in a plane parallel thereto, and the end of the door arm being terminated in a plane substantially parallel with the plane of the door supporting member and being provided with an end wall.

6. A railway car of the twin hopper type having a hinged door with its free edge extending transversely of the car near the rail, an arm secured to the door near the free

edge thereof and extending outwardly beyond the edge of the door and beyond the car side, and a door supporting member pivoted upon the side of the car and adapted to supportingly engage the said arm, the 40 plane of the portion of the car side carrying said member being inclined at an acute angle to the vertical, the said arm being provided with a locking face arranged at right angles to said portion of the car side, 45 said locking face being adapted for co-operation with said supporting member and being further provided with an end wall adapted to retain the door supporting member in engaged relationship with said locking face, said end wall being in a plane normal to the said locking face of the arm.

7. A railway car of the twin hopper type having a hinged door with its free edge extending transversely of the car near the rail, 50 an arm secured to the door near the free edge thereof and having an end projecting outwardly beyond the edge of the door and beyond the car side, the upper part of said end extending outwardly beyond the lower portion thereof, and a door supporting member pivoted upon the side of the car and adapted to supportingly engage the projecting end 55 of said arm, the portion of the car side carrying the said door supporting member being inclined, and the said door supporting member operating in an inclined plane.

In testimony whereof I affix my signature.

WILLIAM E. WINE.
